CLAIM

The ornamental design for a fluted appliance as shown and described.

DESCRIPTION

FIG. 1 is a perspective view of a fluted appliance showing the new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a front view thereof, illustrating the location of various cross-sectional views;

FIG. 9 is a cross-sectional view thereof, taken along line 9-9 of FIG. 8;

FIG. 10 is an enlarged view of a portion of the cross-sectional view of FIG. 9;

FIG. 11 is a cross-sectional view thereof, taken along line 11-11 of FIG. 8;

FIG. 12 is an enlarged view of a portion of the cross-sectional view of FIG. 11;

FIG. 13 is a cross-sectional view thereof, taken along line 13-13 of FIG. 8; and,

FIG. 14 is an enlarged view of a portion of the cross-sectional view of FIG. 13.

The ornamental design of the fluted appliance includes the vertically-extending flutes shown in the figures. The broken lines illustrate portions of the fluted appliance that do not

(Continued)

form any part of the claimed design. The dot dot dash lines illustrate a boundary of the claimed design and form no part of the claimed design.
